US007735169B2

(12) **United States Patent**
Wassilefsky

(10) **Patent No.:** **US 7,735,169 B2**
(45) **Date of Patent:** ***Jun. 15, 2010**

(54) **COMFORT PILLOW**

(75) Inventor: **Gerda Wassilefsky**, Odense V (DK)

(73) Assignee: **Tempur-Pedic Management, Inc.**,
Lexington, KY (US)

(*) Notice: Subject to any disclaimer, the term of this
patent is extended or adjusted under 35
U.S.C. 154(b) by 0 days.

This patent is subject to a terminal dis-
claimer.

(21) Appl. No.: **12/198,537**

(22) Filed: **Aug. 26, 2008**

(65) **Prior Publication Data**

US 2008/0307581 A1 Dec. 18, 2008

Related U.S. Application Data

(63) Continuation of application No. 11/443,460, filed on
May 30, 2006, now Pat. No. 7,415,742, which is a
continuation of application No. 10/489,233, filed as
application No. PCT/US03/16486 on May 23, 2003,
now Pat. No. 7,051,389.

(60) Provisional application No. 60/383,169, filed on May
24, 2002.

(51) **Int. Cl.**

A47G 9/10 (2006.01)

(52) **U.S. Cl.** **5/636**; 5/655.9; 5/953;
5/490

(58) **Field of Classification Search** 5/636,
5/644, 645, 490, 655.9, 953, 654, 655.4,
5/911

See application file for complete search history.

**CROSS-REFERENCE TO RELATED
APPLICATIONS**

This is a continuation application of U.S. patent application Ser. No. 11/443,460 filed on May 30, 2006 and issued on Aug. 26, 2008 as U.S. Pat. No. 7,415,742, which is a continuation of U.S. patent application Ser. No. 10/489,233 filed on Mar. 10, 2004 and issued on May 30, 2006 as U.S. Pat. No. 7,051,389, which is a 35 U.S.C. §371 National Stage Entry Application of PCT Application Number PCT/US03/16486 filed on May 23, 2003, which claims priority to U.S. Provisional Patent Application Ser. No. 60/383,169 filed on May 24, 2002. Priority is hereby claimed to all of these patent applications, the entire contents of which are incorporated herein by reference.

FIELD OF THE INVENTION

This invention relates generally to pillows or cushions, and more particularly to a pillow or cushion for therapeutic use.

BACKGROUND OF THE INVENTION

The neck of a person lying in a supine or sidelying position is often out of alignment with the person's spine. This is commonly the case when the person's neck is supported by a pillow or multiple pillows such that the neck lies at an angle defined by the deflected height of the pillow(s), and this angle is typically not co-planar with the spine. The deflected height of the pillow is closely related to its stiffness, which is conventionally provided by filling material disposed within a fabric covering. Conventional filling material can include feathers, cotton, or a synthetic filler.

SUMMARY OF THE INVENTION

To provide a pillow structure more likely to properly align the user's neck and spine, the invention provides a pillow having multiple foam components.

One embodiment of the present invention includes a pillow having a viscoelastic sleeve defining a cavity and a plurality of loose pieces of filler material substantially enclosed within the cavity.

Another embodiment of the present invention includes a pillow having a first layer of viscoelastic material and a second layer of viscoelastic material. The first and second layers couple together to form a cavity therebetween. A plurality of loose pieces of filler material is positioned between the first and second layers and is enclosed within the cavity.

Yet another embodiment of the present invention includes a method of manufacturing a pillow including coupling a first peripheral edge of a first panel of viscoelastic material to a second peripheral edge of a second panel of viscoelastic material and enclosing a plurality of loose pieces of filler material between and within the first and second panels of viscoelastic material.

The viscoelastic foam responds to changes in temperature such that body heat molds the pillow to conform to the curves of a body for comfort and support. This allows the shape of the pillow to more closely follow the contours of the body and to promote an improved alignment of the neck and spine when a person is in a supine or sidelying position.

A cover preferably encases the pillow and contours to the shape of the pillow. The cover is removable, washable, and has a resealable slot through which the pillow may be inserted

2

or removed. The slot extends across an edge portion of the pillow and is preferably opened and closed by a zipper.

BRIEF DESCRIPTION OF THE DRAWINGS

5 FIG. 1 is a perspective view illustrating a pillow embodying the present invention.

FIG. 2 is an exploded view of the pillow shown in FIG. 1.

10 FIG. 3 is a partial cross-sectional view of the pillow shown in FIG. 1.

DETAILED DESCRIPTION

15 Before the embodiments of the invention are explained in detail, it is to be understood that the invention is not limited in its application to the details of construction and the arrangements of components set forth in the following description or illustrated in the drawings. The invention is capable of other embodiments and of being practiced or of being carried out in 20 various ways. Also, it is to be understood that the phraseology and terminology used herein is for the purpose of description and should not be regarded as limiting.

25 FIGS. 1-3 illustrate a pillow 10 of the present invention having a sleeve construction formed of multiple layers. The 30 pillow 10 comprises a filler material 14 disposed between layers of viscoelastic foam 18. The viscoelastic foam layers 18 possess specific thermally responsive properties which cause the pillow 10 to conform to the shape of the portion of a person's body that contacts the pillow 10. The viscoelastic foam layers 18 have a lower stiffness or hardness at an elevated temperature as compared to the stiffness at a cooler temperature. Conversely, conventional pillow filler materials 35 typically have a constant stiffness with respect to a changing temperature. The body heat of the person acts to soften the portion of the pillow 10 in contact with the body, while the portion of the pillow 10 not contacting the body remains more firm. As a result, the pillow 10 embodying the present invention allows for greater comfort over a conventional pillow by accommodating each user's body form.

40 In one embodiment of the present invention, the filler material 14 is granulated, or shredded, viscoelastic foam having a

density of about 85 kg/m³. However, a suitable density for the

viscoelastic foam filler material 14 for an average weight

pillow 10, for example, can be between about 30 and about

45 140 kg/m³. Further, a suitable density for the viscoelastic

foam filler material 14 for a light-weight pillow 10, for

example, can be less than about 40 kg/m³. Likewise, a suit-

able density for the viscoelastic foam filler material 14 for a

heavy-weight pillow 10, for example, can be greater than

50 about 130 kg/m³. Alternatively, the granulated viscoelastic

foam utilized as the filler material 14 can have any density in

accordance with the desired characteristics of the pillow 10.

In addition, a suitable viscoelastic foam filler material 14

55 possesses an indentation load deflection, or "ILD," of 65%

between 100-500 N loading, and a maximum 10% rebound

according to the test procedure governed by the ASTM-D-1564 standard.

The granulated filler material 14 can be made up of recycled, virgin, or scrap viscoelastic material. The granu-

60 lated filler material 14 may consist of pieces of a nominal

length, or the granulated filler material 14 may consist of

pieces of varying lengths. For example, granulated filler

material 14 may have a nominal length of about 1.3 cm. Also,

granulated filler material 14 may consist of varying lengths

65 between about 0.6 cm and about 2 cm. The granulated filler

material 14 can be as short as 0.3 cm and as long as 4 cm., or

the filler material 14 can be any length in accordance with the

desired characteristics of the pillow 10. In one preferred embodiment of the invention, the granulated filler material 14 is comprised of 16-20% having a length longer than 2 cm, 38-42% having a length between 1 and 2 cm, and 38-42% of the pieces shorter than 1 cm. Significant cost savings and waste reduction can be realized by using scrap or recycled filler material 14 rather than virgin filler material 14. The viscoelastic foam used as the filler material 14 is made from a polyurethane foam material, however, the filler material 14 can be made from any other viscoelastic polymer material that exhibits similar thermally-responsive properties.

The composition of the filler material 14 can be varied to alter the characteristics of the pillow 10 and the cost of the pillow 10. In another embodiment of the present invention, the filler material 14 is a combination of granulated viscoelastic foam and a fiber material. The fiber material can be made from any kind of textile, such as an organic textile (cotton) or a synthetic textile, which is often less expensive than viscoelastic foam. In one embodiment of the present invention, the fiber material has a density of about 1 g/cm³. However, a suitable density for the fiber material for an average weight pillow 10, for example, is 0.1-2 g/cm³. Further, a suitable density for the fiber material for a light-weight pillow 10, for example, can be less than about 0.3 g/cm³. Likewise, a suitable density for the fiber material for a heavy-weight pillow 10, for example, can be greater than about 1.8 g/cm³. Alternatively, the fiber material utilized in combination with the granulated viscoelastic foam as the filler material 14 can have any density in accordance with the desired characteristics of the pillow 10.

In one preferred embodiment of the invention, the filler material 14 is comprised of about 50% fiber material, while the remaining composition includes the granulated viscoelastic foam. However, a suitable range of fiber material in the filler material 14 for an average-cost pillow 10, for example, can be between about 20% and about 80%. Further, a suitable range of fiber material in the filler material 14 for a more expensive pillow 10, for example, can be more than about 30% of the filler material 14. Likewise, a suitable range of fiber material in the filler material 14 for a less expensive pillow 10, for example, can be greater than about 70% of the filler material 14.

In yet another embodiment of the present invention, the filler material 14 is a combination of granulated viscoelastic foam and polystyrene balls, which are often less expensive than viscoelastic foam. The filler material 14 of this embodiment can also include an organic or synthetic fiber material depending on the desired characteristics of the pillow 10. The polystyrene balls may consist of balls of a nominal diameter, or the polystyrene balls may consist of balls of varying diameters. For example, the polystyrene balls may have a nominal diameter of about 5 mm. Also, the polystyrene balls may consist of varying diameters between about 1 mm and about 10 mm. The polystyrene balls can also be as small as 0.5 mm and as long as 20 mm, or the polystyrene balls can be any length in accordance with the desired characteristics of the pillow 10.

In one preferred embodiment of the invention, the filler material 14 is comprised of about 50% polystyrene balls, while the remaining composition includes the granulated viscoelastic foam. However, a suitable range of polystyrene balls in the filler material 14 for an average-cost pillow 10, for example, can be between about 20% and about 80%. Further, a suitable range of polystyrene balls in the filler material 14 for a more expensive pillow 10, for example, can be less than about 30% of the filler material 14. Likewise, a suitable range

of polystyrene balls in the filler material 14 for a less expensive pillow 10, for example, can be greater than about 70% of the filler material 14.

In another embodiment of the present invention, the filler material 14 can also include granulated highly-elastic ("HE") foam in addition to the granulated viscoelastic foam. HE foam is often less expensive than viscoelastic foam, thus yielding a potentially less expensive pillow 10. The filler material can be comprised of any single filler described above or any combination of the fillers. Alternatively, the filler material 14 can also include any conventional materials, such as feathers, granulated cotton, cotton fibers, etc. In one embodiment of the present invention, the filler material 14 includes HE foam having a density of about 35 kg/m³. However, a suitable density for the HE foam for an average weight pillow 10, for example, can be between about 20 and about 50 kg/m³. Further, a suitable density for the HE foam for a lightweight pillow 10, for example, can be less than about 25 kg/m³. Likewise, a suitable density for the HE foam for a heavy-weight pillow 10, for example, can be greater than about 45 kg/m³. Alternatively, the HE foam utilized in the filler material 14 can have any density in accordance with the desired characteristics of the pillow 10.

The granulated HE foam may consist of pieces of a nominal length, or the granulated HE foam may consist of pieces of varying lengths. For example, the granulated HE foam may have a nominal length of about 1.3 cm. Also, the granulated HE foam may consist of varying lengths between about 0.6 cm and about 2 cm. The granulated HE foam can be as short as 0.3 cm and as long as 4 cm., or the granulated HE foam can be any length in accordance with the desired characteristics of the pillow 10. In one preferred embodiment of the invention, the granulated HE foam is comprised of 16-20% having a length longer than 2 cm, 38-42% having a length between 1 and 2 cm, and 38-42% of the pieces shorter than 1 cm.

In one preferred embodiment of the invention, the filler material 14 is comprised of about 50% granulated HE foam, while the remaining composition includes the granulated viscoelastic foam. However, a suitable range of HE foam in the filler material 14 for an average cost pillow 10, for example, is 20%-80%. Further, a suitable range of granulated HE foam in the filler material 14 for a more expensive pillow 10, for example, can be less than about 30% of the filler material 14. Likewise, a suitable range of granulated HE foam in the filler material 14 for a less expensive pillow 10, for example, can be greater than about 70% of the filler material 14.

As previously mentioned, the filler material 14 is disposed between layers of viscoelastic foam 18. In one embodiment of the present invention, the layers of viscoelastic foam 18 have a density of about 85 kg/m³. However, a suitable density for the layers of viscoelastic foam 18 for an average weight pillow 10, for example, can be between about 30 and about 140 kg/m³. Further, a suitable density for the layers of viscoelastic foam 18 for a lightweight pillow 10, for example, can be less than about 40 kg/m³. Likewise, a suitable density for the layers of viscoelastic foam 18 for a heavyweight pillow 10, for example, can be greater than about 130 kg/m³. Alternatively, the layers of viscoelastic foam 18 can have any density in accordance with the desired characteristics of the pillow 10.

The layers of viscoelastic foam 18 are preferably about 10 mm thick and have thermally-responsive properties similar to the granulated viscoelastic foam of the filler material 14. Likewise, a suitable thickness for the layers of viscoelastic foam 18 for an average weight pillow 10, for example, can be between about 5 mm and 15 mm. However, a suitable thickness for the layers of viscoelastic foam 18 for a lightweight

pillow 10, for example, can be less than about 7 mm. Further, a suitable thickness for the layers of viscoelastic foam 18 for a heavyweight pillow 10, for example, can be greater than about 13 mm. The layers of viscoelastic foam 18 are made from a polyurethane foam material, however, the layers of viscoelastic foam 18 can be made from any other viscoelastic polymer material that exhibits similar thermally-responsive properties.

The overall stiffness or hardness of the pillow 10 is dependent on the stiffness of the individual viscoelastic foam layers 18 and the filler material 14. As such, the overall stiffness or hardness of the pillow 10 may be affected by varying the stiffness of the individual viscoelastic foam layers 18 and/or the filler material 14.

As shown in FIGS. 1-3, reinforcing fabric layers 22 are positioned on the outside of the layers of viscoelastic foam 18. The reinforcing fabric 22 acts as an anchor for stitches 26 that secure together the layers of reinforcing fabric 22 and the layers of viscoelastic foam 18. Without the reinforcing fabric layers 22, the viscoelastic foam layers 18, which are less durable than the layers of reinforcing fabric 22, would have to directly anchor the stitches 26 such that the filler material 14 is secured between the viscoelastic foam layers 18. In a pillow having this construction (not shown), the viscoelastic foam layers 18 would likely tear near the stitches 26 as a result of normal use of the pillow. Further, if the viscoelastic foam layers 18 were to tear, then the filler material 14 would spill out. Therefore, the reinforcing fabric layers 22 provide a measure of durability to the pillow 10. The reinforcing fabric 22 is preferably made from a durable material, such as a cotton/polyester blend.

A cover 30 surrounds and encases the pillow 10, and conforms to the shape of the pillow 10. The cover 30 is preferably made from a durable and washable fabric material, such as a cotton/polyester blend. As shown in FIG. 1, a slot 34 extends across the cover 30 along the cover's edge. The pillow 10 may be inserted into the cover 30 through the slot 34. The pillow 10 may also be removed from the cover 30 through the slot 34 to facilitate cleaning of the cover 30. The slot 34 is resealable to close the cover 30 around the pillow 10 and to open the cover 30 for removing the pillow 10. A closure device is used to open and close the slot 34. In the preferred embodiment, the closure device is a zipper 38, although the closure device could also comprise snaps, buttons, hook and loop fasteners, overlapping flaps, laces, or other similar fasteners.

During manufacture, the layers of viscoelastic foam 18 are sewn together with the layers of reinforcing fabric 22 to form a sleeve or casing having an open end, wherein the layers of viscoelastic foam 18 comprise the inner layers of the casing and the layers of reinforcing fabric 22 comprise the outer layers of the casing. The filler material 14 is then inserted through the open end of the casing until the desired amount of filler material 14 is reached within the casing. The open end is then sewn closed, thereby encasing the filler material 14 within the casing and defining a pillow 10. The pillow 10 is then inserted within the cover 30 and the cover 30 is closed by the zipper 38.

I claim:

1. A pillow comprising:
a viscoelastic sleeve defining a cavity; and
a plurality of loose pieces of filler material substantially enclosed within the cavity.
2. The pillow of claim 1, further comprising a cover substantially enclosing the sleeve.
3. The pillow of claim 2, wherein the cover comprises a resealable fastener through which access to the sleeve is obtained.

4. The pillow of claim 1, wherein the sleeve comprises first and second panels of material joined together at peripheral seams to define the internal cavity.

5. The pillow of claim 1, wherein the viscoelastic sleeve has a density between about 30 kg/m³ and about 140 kg/m³.

6. The pillow of claim 1, wherein the plurality of loose pieces of filler material has a nominal length between about 0.6 cm and about 2 cm.

7. The pillow of claim 6, wherein the plurality of loose pieces of filler material has a nominal length of about 1.3 cm.

8. The pillow of claim 1, wherein approximately 16% to 20% of the plurality of loose pieces of filler material includes lengths longer than about 2 cm.

9. The pillow of claim 1, wherein approximately 38% to 42% of the plurality of loose pieces of filler material includes lengths between about 1 cm and about 2 cm.

10. The pillow of claim 1, wherein approximately 38% to 42% of the plurality of loose pieces of filler material includes lengths shorter than about 1 cm.

11. The pillow of claim 1, wherein the filler material further includes a plurality of balls.

12. The pillow of claim 1, wherein the filler material further includes highly-elastic foam.

13. A pillow comprising:
a first layer of viscoelastic material; and
a second layer of viscoelastic material, the first and second layers coupled together to form a cavity therebetween;
wherein a plurality of loose pieces of filler material is positioned between the first and second layers and is enclosed within the cavity.

14. The pillow of claim 13, wherein the first and second layers of viscoelastic material are sewn together.

15. The pillow of claim 13, further comprising a cover substantially enclosing the first and second layers of viscoelastic material and the plurality of loose pieces of filler material.

16. The pillow of claim 15, wherein the cover comprises a resealable fastener through which access to the first and second layers of viscoelastic material is obtained.

17. The pillow of claim 13, wherein the viscoelastic material of the first and second layers has a density between about 30 kg/m³ and about 140 kg/m³.

18. The pillow of claim 13, wherein the plurality of loose pieces of filler material has a nominal length between about 0.6 cm and about 2 cm.

19. The pillow of claim 13, wherein the plurality of loose pieces of filler material has a nominal length of about 1.3 cm.

20. The pillow of claim 13, wherein approximately 16% to 20% of the plurality of loose pieces of filler material includes lengths longer than about 2 cm.

21. The pillow of claim 13, wherein approximately 38% to 42% of the plurality of loose pieces of filler material includes lengths between about 1 cm and about 2 cm.

22. The pillow of claim 13, wherein approximately 38% to 42% of the plurality of loose pieces of filler material includes lengths shorter than about 1 cm.

23. The pillow of claim 13, wherein the filler material further includes a plurality of balls.

24. The pillow of claim 13, wherein the filler material further includes highly-elastic foam.

25. A method of manufacturing a pillow comprising:
coupling a first peripheral edge of a first panel of viscoelastic material to a second peripheral edge of a second panel of viscoelastic material; and
enclosing a plurality of loose pieces of filler material between and within the first and second panels of viscoelastic material.

26. The method of claim **25**, further comprising inserting the plurality of loose pieces of filler material between the first and second panels after coupling the first peripheral edge to the second peripheral edge.

27. The method of claim **25**, further comprising inserting the panels of viscoelastic material and the plurality of loose

5 pieces of filler material into a cover with a resealable slot and sealing the slot to keep the material within the cover.

28. The method of claim **25**, further comprising shredding material into individual lengths to form the filler material.
